UNITED STATES PATENT OFFICE.

EDWARD N. PAGELSEN, OF DETROIT, MICHIGAN.

CUTTING-OFF MECHANISM FOR TUBE-MACHINES.

1,033,454.

Specification of Letters Patent. Patented July 23, 1912.

Application filed May 6, 1912. Serial No. 695,373.

To all whom it may concern:

Be it known that I, EDWARD N. PAGELSEN, a citizen of the United States, and a resident of the city of Detroit, in the county of Wayne and State of Michigan, have invented a new and Improved Cutting-Off Mechanism for Tube-Machines, of which the following is a specification.

This invention relates to means for cutting into predetermined lengths the tubes formed on machines constructed so as to spirally wind a plurality of bands of proper material into tubes of the desired size, and its object is to provide a cutting-off mechanism which shall be simple in construction, effective in operation, and which shall be controlled by the tube as it is being wound.

This invention comprises a revoluble arbor, a cutting tool slidably mounted thereon but revoluble therewith, bearings and a carriage for said arbor, pneumatic means for moving the cutting tool toward and from the tube, and pneumatic means for sliding the tool on the arbor back to starting position after a tube has been severed.

It further consists in combination with said cutting-off mechanism and pneumatic means for positioning the same, of proper valves for controlling the pneumatic devices, of means actuated by the tube when it has reached a proper length to position one of the valves to cause the arbor to be moved toward the tube, and means connected to the arbor-supporting means, to cause the cutter to be moved longitudinally of the arbor to normal position after the arbor has been moved back from the tube.

Machines for spirally winding bands of paper, straw-board and similar material into tubes, are well known, and the production of spirally-wound tubes has become large. As these machines are continuous in their operation, it is necessary to cut the tube into proper lengths so that they may be further operated upon by other machines. These tube machines, as a rule, are so constructed that the finished tube moves longitudinally and at the same time revolves at considerable speed. It is therefore necessary that the cutting-off mechanism be so designed that the cutting tool may freely move longitudinally with the tube during the cutting operation. Where springs or weights are employed to return the cutter to its normal position after a section of tube has been severed, the tool

usually roughens or chews up the tube material at the point where it engages. To prevent this, it is necessary that the tool be permitted to move longitudinally with the tube with the least possible restraint, and that the tool be withdrawn suddenly from the tube after the cutting has been completed.

In the accompanying drawings Figure 1 is a plan and Fig. 2 is a rear end elevation of this improved cutting-off mechanism. Fig. 3 is a section and Fig. 4 an elevation of one of the controlling valves. Fig. 5 is a central, longitudinal section of the saw arbor. Fig. 6 is a vertical, transverse section of the machine through the cylinder for moving the cutting tool toward and from the tube. Fig. 7 is a central, horizontal section of the valve chamber of this cylinder, the valve being shown in plan. Fig. 8 is a front end elevation of the mechanism on a larger scale than Fig. 2. Fig. 9 is an elevation on a larger scale of the arm in the path of the tube. Fig. 10 is an elevation of the arm which actuates the main valve shown in Fig. 7.

Similar reference characters refer to like parts throughout the several views.

This cutting-off mechanism is adapted to be used with any type of machine which produces tubing by spiral winding. The winding mandrel 1 is shown in Fig. 8 and the tube 2 thereon is also shown in Figs. 1 and 2. The base of this machine is indicated in Figs. 2 and 8 and comprises a top 3 on which the cutting-off mechanism is mounted. Any other desired support may be employed, that shown being that of the Osborn Patent No. 945,862, dated Jan. 11, 1910. While any desired means may be employed to drive the cutting tool of this cutting-off mechanism, I have shown the shaft C of this patent and the pulley 59 thereon.

Mounted on the top 3 is a frame having a bottom plate 4, sides 5, provided with slots 6 and a projecting plate 7 to receive the operating cylinder. An arbor 8 is revoluble in bearings 9, carried by the arms 10 which are connected to the slideable plate 11, which plate has projections 12 which extend through the slots 6. This plate, arms and bearings constitute the arbor carriage. This carriage is slideable toward and from the tube 2. Secured to the arbor is a pulley 14 around which extends a belt 15, which also extends around the pulley 59 and the station-

ary idler 16, mounted on the pin 17. An arm 18 is pivoted on the pin 19 and carries a pin 20 on which is revoluble the idler 21, held against the belt 15 by means of the 5 spring 22. By these or other desirable means the belt is kept tight during the time the saw moves toward and from the tube 2.

Compressed air may be supplied from any desired source by means of a main 24, to 10 which connects a pipe 25 which also connects to the valve chamber 26, more fully shown in Fig. 7. The passages 27 and 28 extend from the valve chamber to the ends of the cylinder 29, mounted on the plate 7, which 15 cylinder is provided with heads 30 and 31, a piston 32, and a piston rod 33 which has a pin 34 at its outer end that extends through the flanges 35 on the arbor carriage. The valve chamber is open at its ends so that the 20 exhaust may escape freely. A dumb-bell valve formed by the stem 37 and collars 38 and 39 is slidable in the chamber, and the inlet port is never closed, so that the valve is perfectly balanced. It is moved to the 25 right (Fig. 1) by means of a connecting rod or wire 40, and to the left by means of a spring 41 between the ring 42 and the washer 43. Nuts 44 on the valve stem adjust the tension of the spring.

30 The arbor 8 is preferably a hollow tube, held in proper longitudinal position by the pulley 14 and a collar 45. The cutting tool, preferably a saw 46, is mounted on the collar 47 and held in place by the ring 48 screwed 35 onto the collar. A slot 49 in this arbor receives a pin 50 carried by the collar 47 so that the saw will revolve with the arbor at all positions on the same.

Projecting rearwardly from the frame is 40 a bar 52, preferably hollow, which carries a standard 53 in which a cross shaft 54 is revolvably mounted. This shaft carries an arm 55, (Fig. 9) which extends down into the path of the finished tube, and preferably 45 has a revoluble sleeve 56 to decrease friction, the sleeve being held in place by means of a screw 57. The arm 58, (Fig. 10) also secured to this shaft 54, has the outer end of the rod or wire 40 connected to it, preferably 50 by the eye-bolt 60 and the nuts 61.

The normal position of the parts is as 55 shown in Fig. 1. When the tube engages the arm and swings it outward, the arm 58 will pull the valve stem 37 to the position shown in Fig. 7, thus opening the passage 27 to the compressed air and connecting the passage 28 to the outside atmosphere. The piston 32, the arbor-carriage, the arbor and the cutter will at once be moved toward the 60 tube and the cutter will engage the tube sufficiently to be carried along with the tube. When the outer portion of the tube is severed, it will fall, thus releasing the arms 55 and 58 and the valve stem, whereupon the 65 spring 41 will move the valve collars to the

positions indicated in dotted lines in Fig. 7, when the passage 28 will connect to the compressed air and the passage 27 to the outside atmosphere. As a result the arbor and saw will be moved back from the tube. The saw will still be at the right end of its stroke. To 70 return it, a cylinder 60 (Fig. 5) is mounted in line with the bore of the arbor. In this cylinder is freely slidable the piston 62 to which is connected the rod 63 and the collar 64 provided with a groove 65 to receive the end of the pin 50. The piston, rod and collar slide outwardly to the positions indicated in dotted lines, with the saw when that moves with the tube.

80 Mounted on a side of the frame is a valve body 67 having a plug 68 to which is connected a lever 69. See Figs. 1, 3 and 4. A pipe 71 connects this valve to the air main 24 and another pipe 70 connects it to the cylinder 60. An arm 72 on the carriage engages the lever 69 when the carriage is in the position shown in Fig. 1 and turns the plug 68 to the position shown in Fig. 3. Air will now rush to the outer end of the cylinder 60 and force the piston 62 and the saw back to the positions shown in Fig. 5. The saw will thus be held at the left or normal end of its stroke during the time it is held away from the arbor. As soon as the carriage and saw move toward the tube, the lever 69 of this valve is released and the spring 74 will turn the plug about sixty degrees, so as to cut off the supply of air and to connect the pipe 70 with the escape port 75 in the valve body. It will therefore be seen that during the time the cutter moves with the tube, there is nothing to hinder its movements, so that it can move freely and avoid injuring the tube. The movements 105 toward and from the tube can be regulated by the sizes of the small holes through the wall of the cylinder 29. After the cutter has performed its duty, it is immediately moved away from the tube and then back to normal 110 position, where it is held by pneumatic pressure until it is again moved toward the tube, when this pressure is immediately removed. Instead of the saw, a disk with a sharp, 115 smooth edge may be employed.

To steady the tube, a forked arm 77 may be mounted on the support 52 as shown in Fig. 1 and in dotted lines in Fig. 2.

Many changes in the proportions and details of this construction may be made by 120 those skilled in this art without departing from the spirit of my invention as expressed in the claims. Thus the distance between the bearings 9 of the arbor and the length of the cylinder 60 and rod 63 may be increased 125 to permit a proportionally longer longitudinal movement of the cutting tool. All the parts may be made adjustable in the usual manner to permit this mechanism to be adapted for tubes of different diameters. As 130

the weight of the arms 55 and 58 needs be but small, they will have no undesirable effect on the operation of the mechanism. The position of the guide 77 may be varied 5 as desired.

I claim.

1. In a cutting-off mechanism for tube-machines, the combination of an arbor, means to revolve the same, a cutter slideable on said 10 arbor and revolute therewith, a slideable carriage for said arbor, pneumatic means for moving said carriage to carry the arbor toward and from the tube, said cutter slideable on the arbor under pressure of the tube, 15 and pneumatic means for sliding back the cutter on the arbor to original position.

2. In a cutting-off mechanism for tube-machines, the combination of an arbor, means to revolve the same, a cutter slideable on said 20 arbor and revolute therewith, a slideable carriage for said arbor, pneumatic means for moving said carriage to carry the arbor toward and from the tube, said cutter slideable on the arbor under pressure of the tube, 25 pneumatic means for sliding back the cutter on the arbor to original position, and controlling means actuated by the tube to cause the pneumatic means to move the arbor toward the tube.

3. In a cutting-off mechanism for tube-machines, the combination of an arbor, means to revolve the same, a cutter revolute with 30 said arbor and slideable thereon under action of the tube, a slideable support for said arbor, 35 a pneumatic cylinder and piston for sliding said support to carry the arbor toward and from the tube, a valve to control the operation of said piston, an arm in the path of the tube, means connecting said arm to said 40 valve whereby the movement of said arm by the tube will cause the piston to move said arbor toward the tube, a spring to move the valve to normal position, and means to slide the cutter back to starting position on the 45 arbor.

4. In a cutting-off mechanism for tube-machines, the combination of a revolving arbor, a cutting tool revolute therewith and slideable thereon under action of the tube, a 50 pneumatic cylinder and piston for moving the arbor toward and from the tube, and a pneumatic cylinder and piston for moving the cutting tool on the arbor back to normal position.

5. In a cutting-off mechanism for tube-machines, the combination of a hollow revolute arbor, means to move the arbor toward 55 and from the tube, a cutter slideable on said arbor and freely movable longitudinally outward by the tube, a rod slideable within the arbor, means to slide the rod inward, and

connecting means between the rod and the cutter.

6. In a cutting-off mechanism for tube-machines, the combination of a hollow revolute arbor, means to move the arbor toward 65 and from the tube, a cutter slideable on said arbor and freely movable longitudinally outward by the tube, a rod slideable within the arbor, a pneumatic cylinder mounted co-axially with the arbor, a piston within the cylinder connected to said rod, connecting means between the rod and the cutter whereby the cylinder and piston may return the 70 cutter to normal position, and means to control the operation of said pneumatic cylinder and piston.

7. In a cutting-off mechanism for tube-machines, the combination of a hollow revolute arbor, means to move the arbor toward 80 and from the tube, a cutter slideable on the arbor and freely movable outwardly on the arbor by the tube, and means freely movable outwardly by the cutter to move the cutter 85 inwardly on the arbor after the arbor has been moved back from the tube.

8. In a cutting-off mechanism for tube machines, the combination of a frame, a carriage slideable thereon, a revolute arbor mounted on said carriage, a cylinder mounted 90 on said frame, a piston therein, a rod connecting the piston to said carriage, a valve to control the flow of fluids under pressure to said cylinder, means in the path of the manufactured tube for moving the valve in one 95 direction to cause the fluid to move the arbor toward the tube, a spring to return the valve to normal position to cause the fluid to move the arbor from the tube, a cutter slideable outwardly on the arbor by the tube 100 when in engagement with the same, and means to slide the cutter inwardly to normal position.

9. In a cutting-off mechanism for tube-machines, the combination of a hollow revolute arbor, means to move the same toward 105 and from the tube to be cut, a cutter slideable on the arbor and freely movable longitudinally outward by the tube, and normally inoperative means mounted co-axially with 110 said arbor for sliding the cutter inwardly to normal position, and a controlling device for causing said cutter-sliding means to be energized when the arbor has been moved back from the tube.

In testimony whereof I have signed this specification in the presence of two subscribing witnesses.

EDWARD N. PAGELSEN.
